UNITED STATES PATENT OFFICE.

GEORGE ROTTMAN, OF NEW YORK, N. Y.

BUCKLE.

1,394,644.

Specification of Letters Patent. Patented Oct. 25, 1921.

Application filed January 12, 1920. Serial No. 350,944.

To all whom it may concern:

Be it known that I, GEORGE ROTTMAN, a citizen of the United States, residing in New York, in the county of New York and State 5 of New York, have invented certain new and useful Improvements in Buckles, of which the following is a specification.

My invention relates to an improvement in buckles; especially buckles for belts, 10 straps, bands, flaps, tabs and the like, to fasten the ends thereof together.

An object of my invention is to provide a buckle which is exceedingly simple in construction, and of such design as to be capable 15 of holding the ends of bands, flaps, etc., most securely, thereby eliminating all possibility of the bands or flaps slipping, thus effectually preventing displacement of same; and further presenting a very attractive 20 appearance.

The construction of my invention is particularly set forth in the following specification, taken with the accompanying drawings; which illustrate preferred forms of 25 my improved buckle. The embodiments actually illustrated, however, may of course be varied somewhat, particularly as to the shape, size and the arrangement of the parts, without departing from the nature and spirit 30 of my invention, as indicated by the broad meanings of the terms in which the claims appended hereto are expressed.

On the drawings:—

Figure 1 is a face view of a buckle according 35 to my invention; showing the ends of a belt, or two flaps, for example, connected thereby;

Fig. 2 is a top view of what is shown in Fig. 1;

Fig. 3 is a horizontal section taken on the line 3—3, in Fig. 1;

Fig. 4 is a view similar to Fig. 1; with the parts of the buckle in open position;

Fig. 5 is a face view and Fig. 6 is a longitudinal section of a modification of my buckle;

Fig. 7 is a front view of a further modification; and

Figs. 8 and 9 are respectively an elevation 50 and a section of another modification.

The same numerals identify the same parts throughout.

The buckle is illustrated as comprising a frame 1, which may be made by bending a

piece of wire into the required shape and 55 fastening together the extremities thereof in any approved manner. The top 2 and bottom 3 of the buckle are preferably parallel, but the rear side 4, is bent over at an angle to the plane of the top and bottom, and 60 projects somewhat; whereby this side is offset, as shown particularly in Figs. 2 and 3. The extremities of the top and bottom where they unite with the rear end 4 are joined by a small fixed bar or brace 5, the 65 ends of which are turned over to grip the top and bottom securely. This brace or bar strengthens the buckle and prevents bending of the end 4 by any stress to which it ordinarily may be subjected.

At their opposite or front extremities the top 2 and bottom 3 are doubled upon themselves and these doubled-over portions are joined by the front end or side 6 of the buckle. Between the side 6 and bar 5 is a 70 sliding catch 7, the ends of which are turned over as shown at 8, to provide bearings which slidably engage the top 2 and bottom 3. This catch 7 may be simply a piece of 75 metal, secured to the top and bottom of the buckle as set forth, and slidable toward and from the side 6. The rear edge 9 of this catch adjacent the bar 5 is preferably bent over slightly, and when the catch is slipped along the top 2 and bottom 3, the edge 80 thereof can be moved into direct contact with the forward side 6.

In practice, if the buckle is to be applied to a belt, one extremity 11 of the belt will be secured to the side or end 4 and the other 90 end 12 will be passed over the front side 6 and behind the catch 7. To hold this end 12 fast, the catch will be slipped along the top 2 and bottom 3 until it reaches the front side 6, whereupon the end 12 of the belt 95 will be forced into a recess 10 provided by the body of the catch through bending over the rear edge 9. See Fig. 3. The engagement of the extremity 12 between the forward end 6 and the catch 7 will be tight 100 enough to prevent all slipping and the projecting end 12 of the belt can, if desired, be passed between the rear end 4 and the brace 5.

With the catch engaging end 12, this end 105 can be released by means of a tip 13 projecting from the front edge of the catch. When the end 12 is held fast the tip 13 ex-

tends beyond the end 6 and presses upon the end 12, but has an out-turned end to be grasped between finger and thumb to enable the catch to be moved back, as indicated particularly in Fig. 3.

Thus the ends 11 and 12 of the belt will be securely held and the projecting end 12 can be disposed flat against the end 11 fastened to the end 4. This end by reason of being bent over at an angle out of the plane of the top 2 and bottom 3 holds the end 11 a little farther to the back or inside face of the belt; and just a little out of line with the buckle. Hence, when the extremity 12 is engaged by the buckle, the tip thereof lies against the end 11, and is held in toward the wearer's body, and gives a very neat effect.

Of course, the operation and result will be the same if the extremities 11 and 12 are parts of separate flaps, tabs, straps, etc., instead of belonging to a belt.

The brace 5 is preferably channel-shaped, to make it stronger, except where it is caused to grip the top 2 and bottom 3. Also the catch 7 may be bent or stamped to turn in the rear edge or portion 9 so as to give a rounded recess 10, as shown, or an angular one, if desired, and this bending has the further effect of strengthening the catch. As clearly shown in Fig. 3, tension on the extremities 11 and 12 has the effect of urging the catch toward the end 6, and making the buckle hold tighter because the extremity 12 engages frictionally with the rear edge of the catch and tends to make it press the end 12 against the side 6. The bearings 8, as will be understood, engage the top 2 and bottom 3 so that the catch can be slipped back, away from the side 6, or moved forward, but must not be too loose. Instead of a wire frame 1, a frame stamped out of sheet metal can be utilized. Any other suitable material, too, may be employed.

In Figs. 5 and 6 the buckle is shown as consisting of an open frame as before, with top 2 and bottom 3, rear side or end 4 and front side or end 6. Adjacent the end 4 is a transverse loop-bar 14 and the front end 6 has a rearward extending projection 15 with a transverse aperture 16 therein. This form of buckle is shown as made out of stamped metal. The catch 7 is located between the bar 14 and projection 15 and it has its ends turned over to engage slidably with the top 2 and bottom 3 and provide bearings so that it can be moved, as before, toward and from the end 6. The edge of this catch adjacent the bar 14 is bent over as at 9, to provide the recess 10 on the inner face of the catch 7 and the catch is also furnished adjacent its front end with a tip or projection 17 in line with the aperture 16. To use this buckle, one end of the belt 11 or the like, is attached

to the loop-bar 14 and the other end is intended to be slipped between the projection 15 and the catch 7 and over the rear end 4. When the catch is moved to the right, the end 12 is forced into the recess 10 and a portion of this end will be engaged by the tip 17 and forced to a slight extent into the aperture 16. Thus the end 12 is held by the buckle as securely as when the form shown in the first four views is employed, and can be released by moving the catch back with the tip 17.

In Fig. 7 the buckle illustrated is the same as in Fig. 1, except that the top 2 and bottom 3 are bent to provide shoulders 18 adjacent the end 4 to coöperate with said end in preventing slipping of the bar 5.

The modification shown in Figs. 8 and 9 is similar to the construction presented in Figs. 1, 2, 3, 4 and 7; except that the forward end 6 is a little out of the plane of the top and bottom; and the catch 7 is corrugated and its transverse axis makes a slight angle to the plane of the top and bottom. I provide the corrugations to make the catch stronger; and this side 6 extends a little toward the catch when the catch is near this side. See Fig. 9. This buckle will hold belts, flaps, etc., of varying thickness. If the belt or the like is relatively thick, the end thereof will be gripped between the side 6 and the first corrugation 19; while if it is relatively thin it will be gripped between the side 6 and the rear corrugation 20 because the catch will be moved closer to the end 6.

Having described my invention, what I believe to be new and desire to secure and protect by Letters Patent of the United States is:—

1. A buckle comprising a frame having a forward end, a parallel top and bottom, and a rear end offset from the frame, a channel-shaped brace connecting said top and bottom adjacent said rear end, a catch having its ends slidably engaging said top and bottom to coöperate with said forward end, the extremities of said top and bottom extending beyond said forward end, and said catch having its rear edge bent over to provide a recess to coöperate with the forward end, whereby when the end of a band is passed over said forward end, it may be forced into said recess and secured against said forward end by said catch.

2. A buckle comprising a frame having a top and bottom, a rear end, a loop-bar in front of said rear end, a front end with a rearward extending projection, said projection having a transverse aperture, and a catch slidably engaging the top and bottom, said catch having its rear edge bent over to provide a recess to coöperate with the rear edge of said projection and having a projec-

tion adjacent its front edge to coöperate with the aperture in said first-named projection.

3. A buckle comprising a frame having a forward end, a parallel top and bottom, and a rear end offset from the frame, a brace connecting said top and bottom adjacent said rear end, said top and bottom having shoulders to coöperate with the rear end and prevent movement of the brace, a catch having its ends slidably engaging said top and bottom to coöperate with said forward end, the extremities of said top and bottom extending beyond said forward end, and said catch having its rear edge bent over to provide a recess and a projecting tip at its forward edge to coöperate with the forward end, whereby when the end of a band is

passed over said forward end, it may be forced into said recess and secured against 20 said forward end by said catch and said tip.

4. A buckle comprising a top and a bottom, a forward end and a rear end connecting the top and bottom, a bar joining the top and bottom adjacent said rear end, and 25 a corrugated sliding catch engaging the top and bottom and having a bent portion at its rear edge and a projecting tip at its forward edge to coöperate with the forward end of the buckle, said catch making an angle 30 with the plane of said top and bottom.

In testimony whereof I have signed my name to this specification on this 2nd day of December, 1919.

GEORGE ROTTMAN.
